UNITED STATES PATENT OFFICE

NIELS L. MORTENSEN, OF WHITEFISH BAY, WISCONSIN, ASSIGNOR, BY MESNE ASSIGNMENTS, TO CUTLER-HAMMER, INC., A CORPORATION OF DELAWARE

CONTROLLER FOR ELECTRIC MOTORS

Application filed December 10, 1927. Serial No. 239,146.

This invention relates to controllers for electric motors, and while not limited thereto is particularly applicable to controllers for blast furnace tops.

Blast furnace tops are ordinarily provided with a hopper for receiving material supplied to the furnace. The hopper is rotatable to provide for distribution of the material and the same is usually provided with automatic control means which provides for dumping of a fixed number of loads of material at given points into the furnace. However, in practice it has been found desirable to provide for variation of the number of loads of material dumped at given points into the furnace and the present invention has among its objects to provide a controller for this purpose.

Another object is to provide an automatic controller of the aforesaid character including a control part adapted to be set in different positions for selection of the number of loads to be dumped into the furnace at predetermined points.

Another object is to provide an automatic controller of the aforesaid character which is capable of use in connection with either a single or double bucket skip hoist.

Various other objects and advantages of the invention will hereinafter appear.

The accompanying drawings diagrammatically illustrate an embodiment of the invention which will now be described, it being understood that various changes may be made in the embodiment illustrated without departing from the spirit and scope of the appended claims.

In the drawing,

Figure 1 illustrates schematically and diagrammatically a furnace top controller constructed in accordance with the invention,

Fig. 2 is an across-the-line diagram of the control circuits illustrated in Fig. 1, and

Fig. 3 is a diagrammatic view of one type of furnace top to which the controller shown in Fig. 1 may be applied.

The reference character M designates a direct current motor for operating the hopper of a blast furnace top of the character shown in Fig. 3. The blast furnace top shown in this figure includes a large bell B and a small

bell B¹, each of which is adapted to be opened and reclosed by a suitable operating mechanism. The small bell B¹ is associated with a distributing hopper H and the motor M is geared to said hopper to effect rotation thereof. The material supplied to hopper H is deposited at given points on the large bell B by rotating said hopper to bring the material therein directly above such points and then emptying the hopper by opening the small bell B¹. As hereinafter set forth, the controller illustrated is designed to deposit a selected number of loads of material at six equally spaced points on the large bell B.

Motor M as shown in Fig. 1 is provided with an armature A, a series field F, and a shunt field, F¹, and the same is provided with a well known type of controller including a pair of electromagnetically operated line switches 1 and 2 and a pair of electromagnetically operated accelerating switches 3 and 4 for controlling resistances R¹ and R² in the armature circuit. Switches 3 and 4 are of like construction, each of the same being provided with a contact member pivoted intermediate its ends, and a pair of series operating windings arranged on opposite sides of such pivot. As is well known, during starting of the motor the lower windings of switches 3 and 4 prevent closure thereof under the action of the upper windings until given current conditions exist in the motor circuit.

The line switches 1 and 2 are controlled by an electromagnetically operated timing relay 10 which is under the control of a pair of electromagnetically operated relays 11 and 12. Timing relay 10 is normally open and closing movement thereof is retarded by a dash pot 10^b.

Relay 12, in addition to its aforementioned function, acts through the medium of a pair of switches 13 and 14 to control an electromagnetically operated switch 15. The switch 15 which will be hereinafter termed the "load switch" is adapted to operate in a step by step manner upon dumping of successive loads into the distributing hopper. Relay 12 is controlled by relay 11 and by electromagnetically operated switches 16 and 17. Switch 16 which will

100

be hereinafter termed the "position switch" is controlled by the load switch 15 through the medium of relays 11 and 12 and a selector switch 18. As hereinafter set forth, the 5 position switch is adapted to operate in a step by step manner and is advanced one step each time a selected number of loads of material are dumped into the charging hopper. The switch 17 which will be hereinafter termed the "limit switch" is also 10 adapted to operate in a step by step manner and is under the control of a rotary switch 19. Switch 19 is connected through suitable gearing with the distributing hopper 15 per H and it is assumed that said switch makes one complete revolution upon rotation of the hopper H through an angle of 60 degrees.

The controller also includes a three pole 20 double throw switch 22 which is adapted as hereinafter set forth to commutate certain of the control connections to provide for single or double bucket operation of the controller.

25 The construction and operation of certain of the aforementioned control instrumentalities will now be more fully described. Relay 11 is provided with an operating winding 11^a, a pair of normally closed down contacts 11^b and a pair of normally open up contacts 11^c. Relay 11 is adapted to be held in its attracted position by a latching mechanism having a tripping winding 11^d and for purposes hereinafter 30 set forth the same is provided with normally closed auxiliary contacts 11^e, and normally open auxiliary contacts 11^f. Relay 12 is similar to the relay 11 and the several parts thereof are designated by exponents corresponding to those used in the 35 foregoing description of relay 11.

The control switches 13 and 14 which as before stated control the load switch 15 are normally open and as hereinafter set forth 40 the same are controlled by the skip hoist which furnishes material to the blast furnace top. Control of said switches may be effected in any suitable or well known manner, as by means of a nut 25 which is movable by a screw 26 operatively connected 45 to the skip hoist operating mechanism as shown in Fig. 3.

The load switch 15 hereinbefore referred to is provided with an operating electromagnet 15^a which is adapted when successively energized to rotate a contact member 15^b through the medium of a conventional type of ratcheting mechanism 15^c. The contact member 15^b is provided with a pair 55 of electrically connected contact brushes, one for engaging a series of eight insulated contact buttons, and the other for engaging a series of eight electrically connected contact buttons. The contact member 15^b is 60 adapted to move through a distance corre-

sponding to the spacing of said contacts upon each operation of its associated ratcheting mechanism, and the same is biased to return to the position shown in Fig. 1. A pawl is provided for engaging notches on the periphery of contact member 15^b to hold the latter in its various operative positions and said pawl is adapted to be released by an electromagnet 15^d. For purposes hereinafter set forth normally closed auxiliary contacts 15^e and 15^f and normally open auxiliary contacts 15^g are associated with electromagnet 15^a and normally open auxiliary contacts 15^h are associated with the electromagnet 15^d.

70 The limit switch 17 is similar to the load switch 15 and the various parts thereof are designated by exponents corresponding to those used in the foregoing description of said load switch. One of the contacts carried by the contact member 17^b cooperates with a series of five insulated contacts while the other contact carried by said member cooperates with a series of five electrically connected contacts. The auxiliary contacts 80 associated with the limit switch 17 comprise normally open contacts 17^g associated with the operating electromagnet 17^a and a normally open auxiliary switch 17ⁱ associated with the contact member 17^b. The 85 switch 17ⁱ is adapted to close upon initial movement of the contact member 17^b out of normal position.

90 The position switch hereinbefore referred to is provided with an operating electromagnet 16^a which is adapted to rotate a contact member 16^b through the medium of a ratcheting mechanism 16^c which is similar to that employed in the switches 15 and 17. The contact member 16^b is provided with a pair 95 of contact brushes, one of which cooperates with a series of twenty-four equally spaced insulated contact buttons 16^d and the other of which engages a circular contact ring 16^e. The magnet 16^a and its associated ratcheting mechanism 16^c is adapted to move the contact member 16 in steps through distances corresponding to the spacing of the insulated contact buttons 16^d and for purposes herein- 100 after set forth said magnet has normally open auxiliary contacts 16^g associated therewith.

105 The selector switch 18 comprises a manually operated contact arm having electrically connected contact brushes, one of which is adapted to engage a series of nine insulated contact buttons 18^a, and the other of which is adapted to slide over a contact segment 110 18^b.

115 The function and operation of the afore- 120 described controller together with the circuit connections therefor will now be more fully described in connection with Fig. 2. It is assumed that the switch 22 is in the position shown in Fig. 1, which provides for 125 double bucket operation of the controller.

Dumping of skip hoist bucket No. 1 closes switch 13 and an energizing circuit for the operating coil 15^a of the load switch is then established extending from line L¹ through the auxiliary contacts 15^e, through the operating winding 15^a of said load switch, and thence through the left hand down contacts 11^b of relay 11, through the lower pole of switch 22 and through the switch 13 to line L². Energization of the operating winding 15^a moves the load switch contact element 15^b in counterclockwise direction to position 1 and the same is held therein by its associated pawl. Upon response of the load switch the auxiliary contacts 15^g associated therewith establish an energizing circuit for the closing coil of relay 11 extending from line L¹ to and through said auxiliary contacts, through the middle pole of switch 22, through the closing coil 11^a and through the auxiliary contacts 11^e and switch 13 to line L². Upon response of relay 11 the timing relay 10 is energized by a circuit extending from line L¹ through the right hand contacts 11^c of relay 11, through the right hand down contacts 12^b of relay 12, and thence through the operating winding 10^a of the timing relay to line L². However, upon closure of relay 11 relay 12 is also immediately energized by the circuit extending from line L¹ through the right hand up contacts 11^c of relay 11, through the operating winding 12^a, through the auxiliary contacts 12^e of said relay, through the upper pole of switch 22, and through the zero position contacts of position switch 16 to line L². Thus immediately upon establishment of the afore-described energizing circuit for the timing relay 10 the switch 12 responds to interrupt such energizing circuit whereby said timing relay remains in its normal position.

The relays 11 and 12 are now latched in their attracted positions, and when skip hoist bucket No 2 is brought into its load discharging position the switch 14 is closed. Upon closure of switch 14 the load switch 15 is again operated one step, the winding thereof being energized by a circuit extending from line L¹ through the auxiliary contacts 15^e to and through operating winding 15^a, and thence through the left hand up contacts 11^c and through switch 14 to line L². The load switch is now moved to its second position and is held therein by its associated pawl and the auxiliary contacts 15^g of said load switch establish an energizing circuit for the trip coil 11^d of relay 11, extending from line L¹ through auxiliary contacts 15^e, through said trip coil 11^d and thence through auxiliary contacts 11^f of relay 11, and the switch 14 to line L². Upon tripping of relay 11 a circuit is again made for the timing relay 10, extending from line L¹ through the right hand down contacts 11^b of relay 11, through the right hand up contacts 12^c of relay 12, and thence through the operating winding 10^a of the timing relay to line L². Upon tripping of the relay 12 the aforescribed energizing circuit for the operating coil 15^a of the timing relay is interrupted whereby said timing relay remains in normal position.

relay 12, and thence through the operating winding 10^a of said timing relay to line L². However, at this time a circuit is also made for the trip winding 12^d of relay 12 extending from line L¹ through the right hand down contacts 11^b of relay 11, through the trip coil 12^d of relay 12, through the auxiliary contacts 12^e of said relay, and through the zero position contacts of position switch 16 to line L². Upon tripping of the relay 12 the aforescribed energizing circuit for the operating coil 15^a of the timing relay is interrupted whereby said timing relay remains in normal position.

The aforescribed operations are repeated until the number of loads determined by the setting of selector switch 18 have been dumped at the zero position. Assuming that the selector switch 18 is set in position four, when the fourth load is dumped the operation of the controller is similar to that hereinbefore described in connection with closure of switch 14. However, load switch 15 has moved into its fourth position and as soon as the operating magnet 15^a of said switch and the relays 11 and 12 return to normal position the operating winding of the position switch 16 is energized to move said position switch to its 60 degree point. This energizing circuit extends from line L¹ through the right hand contacts 11^b of relay 11, through the left hand contacts 12^b of relay 12, through auxiliary contacts 15^e of the load switch, through the operating winding 16^a of the position switch, and through the selector switch 18 in its fourth position and the load switch 15 in a corresponding position to line L². In this connection it should be noted that the aforescribed energizing circuit is established in the same manner if the selected number of loads is either six or eight. On the other hand, it should be noted that after dumping of either five or seven loads the relays 11 and 12 are latched in their attracted positions. Thus if the selected number of loads is either five or seven the position switch 16 is energized through the medium of the right hand contacts 11^c of relay 11 and the left hand contacts 12^c of relay 12. Upon response of position switch 16 its associated contacts 16^e establish an energizing circuit for the trip coil 15^d of the load switch extending from line L¹ through the right hand contacts 11^c and the left hand contacts 12^c or the right hand contacts 11^b, and the left hand contacts 12^b, as the case may be, through the auxiliary contacts 15^e of the load switch and through the trip coil 15^d and the auxiliary contacts 16^e of the position switch to line L². Trip coil 15^d in responding maintains itself through the medium of its auxiliary contacts 15^b which shunt the auxiliary contacts 16^e of the position switch. The load switch 15 is then permitted to return to normal position and in returning to nor-

mal position the same interrupts the afore-described energizing circuit for the operating winding 16^a of the position switch.

Assume now that the next load is delivered by skip bucket No. 1, the load switch 15 being in normal position and the position switch 16 being in its 60 degree position. Upon dumping of the load by skip bucket No. 1, switch 13 energizes the load switch 15 as hereinbefore described, moving the same to its first position. Upon response of said load switch the contact 15^f thereof interrupts the aforescribed maintaining circuit for the trip coil 15^d and the pawl associated with said coil drops to normal position to prevent return movement of said load switch to normal position. Also as hereinbefore described, upon response of the load switch 15 the auxiliary contacts 15^g thereof effect response of relay 11 and said relay in turn establishes the aforescribed energizing circuit for the timing relay 10. However, with the position switch on its 60 degree point relay 12 does not respond immediately since the aforescribed energizing circuit for the said relay is opened by movement of the contact member 16^b of the position switch out of its zero position. Thus the timing relay 10 responds against the action of its associated dash pot to connect the operating windings 1^a and 2^a of the line switches 1 and 2 across lines L¹—L² as is apparent from Fig. 2. Closure of said line switches connects motor M across lines L¹—L² through resistances R¹ and R², and thereafter the accelerating switches 3 and 4 operate in a well known manner to exclude said resistances from the motor circuit to bring the motor up to speed. The motor now operates until the hopper H is rotated through an angle of 60 degrees whereupon the rotary switch 19 makes one complete revolution, and as is apparent from Fig. 2 the operating winding 17^a of the limit switch is then connected across lines L¹—L² through the auxiliary contacts 11^e of said limit switch. In responding limit switch 17 moves into its 60 degree position. The relay 12 is now energized by a circuit extending from line L¹ through the right hand contacts 11^e of relay 11, through the operating winding 12^a, through the auxiliary contacts 12^e, through the upper pole of switch 22 and thence through the position switch 16 which is in its 60 degree position and the limit switch 17 which is also in its 60 degree position to line L². Response of relay 12 interrupts the aforescribed energizing circuit for the timing relay 10 and the latter relay in opening disconnects the windings 1^a and 2^a of the line switches from line L¹. However, the windings 1^a and 2^a remain connected to line L¹ through the auxiliary contacts 17^e associated with the limit switch 17 until the operating mechanism of said limit switch returns to normal position whereupon said contacts de-

energize said windings to open the line switches 1 and 2 for stopping of the motor. The rotary switch 19 interrupts the energizing circuit for the limit switch operating winding 17^a upon full movement of the hopper H through an angle of 60 degrees and said limit switch is then permitted to return to normal position since the trip coil 17^d thereof is energized immediately upon response of relay 12. The energizing circuit for trip coil 17^d extends from line L¹ through the right hand contacts 11^e of relay 11 through the left hand contacts 12^e of relay 12 and through said trip coil and the auxiliary contacts 17^f associated with the contact element 17^b to line L².

Assuming now that second load of material is dumped into the hopper H by skip bucket No. 2. As hereinbefore described switch 14 is then closed, which results in movement of the load switch 15 to its second position and tripping of the latching mechanism associated with the relay 11. The controller again operates in a manner similar to that above described to cause the motor M to rotate the load of material in the hopper through an angle of 60 degrees, except that now the timing relay 10 is energized through the medium of the right hand contacts 11^b of relay 11 and the right hand contacts 12^b of relay 12. Also, the timing relay 10 is now deenergized to stop the motor by tripping of relay 12. The tripping circuit for said relay is established from line L¹ through the right hand contacts 11^b of relay 11, through the tripping coil 12^d, through the auxiliary contacts 12^f and through the position switch 16 which is in its 60 degree position and the limit switch 17 which is in a corresponding position to line L². The aforescribed operations are repeated until the number of loads determined by the setting of selector switch 18 have been dumped at the 60 degree point.

Upon dumping of the selected number of loads at the 60 degree point the position switch 16 is again energized in the manner above described to move the same into its 120 degree position. With the position switch 16 in this position the controller operates in the same manner as when said switch was in its 60 degree position, except that now the motor is maintained energized until each load dumped into the hopper H is moved to the 120 degree dumping point. In other words, it is necessary upon dumping of each load into the hopper for the rotary switch 19 to make two revolutions. This causes the limit switch 17 to move into its 120 degree position and said limit switch then acts through the medium of the position switch 16 to cause operation of the relay 12, which as hereinbefore set forth effects stopping of the motor.

In connection with the foregoing, it is ap-

parent that when the selected number of loads have been moved to any of the dumping points the position switch 16 is advanced one step in a clockwise direction. Furthermore, it is apparent from the foregoing that the setting of position switch 16 determines the degree of operation of the motor M upon dumping of each load into the hopper. In other words, when the position switch 16 is in any position other than its zero position the motor M will operate upon dumping of each load into the hopper until the rotary switch 19 moves the limit switch 17 to a position corresponding to that of the position switch whereupon the relay 12 is operated as hereinbefore described to stop the motor.

For single bucket operation of the skip hoist the double throw knife switch 22 is moved from the position shown in Fig. 1 into engagement with its left hand stationary contacts. Also, the operating mechanism for the limit switches 13 and 14 is arranged whereby switch 13 is closed upon lowering of the skip hoist bucket while switch 14 is closed upon movement of the skip hoist bucket into its dumping position.

Assuming that the parts of the controller are in the position shown in Fig. 1, upon lowering of the skip hoist bucket limit switch 13 is closed and establishes an energizing circuit for the operating coil 11^a of relay 11 extending from line L¹ through the middle pole of switch 22, through the operating winding 11^a, through the auxiliary contacts 11^e, and through said limit switch to line L². Relay 11 in responding establishes an energizing circuit for relay 12 extending from line L¹ through the right hand contacts 11^b, through the operating winding 12^a of relay 12, through the auxiliary contacts 12^e of said relay and thence through the upper pole of switch 22 to line L². Relays 11 and 12 in responding are held in their operated positions by their associated latching mechanisms and the operating coils thereof are deenergized through opening of their associated auxiliary contacts 11^e and 12^e.

Upon movement of the skip hoist bucket into its dumping position limit switch 14 is closed and establishes an energizing circuit for the load switch 15 extending from line L¹ through the auxiliary contacts 15^e of said load switch, through the operating winding 15^a thereof and through the left hand contacts 11^c of relay 11 and the limit switch 14 to line L². Upon response of load switch 15 the tripping coil 11^b of relay 11 is energized by a circuit extending from line L¹ through the auxiliary contacts 15^e of the load switch, through the tripping coil 11^b and through the auxiliary contacts 11^e and the limit switch 14 to line L². Upon tripping of the latching mechanism associated with relay 11 said relay returns to normal position and establishes an energizing circuit for tim-

ing relay 10 extending from line L¹ through the right hand contacts 11^b of relay 11, through the right hand contacts 12^c of relay 12, and through the operating winding 10^a of said timing relay to line L². Assuming that the position switch 16 is in its zero position immediately upon energization of the timing relay 10 the trip coil 12^b of relay 12 is energized by a circuit extending from line L¹ through the right hand contacts 11^b of relay 11, through the trip coil 11^b and the auxiliary contacts 12^e of the relay 12 and through the position switch 16 to line L². Thus with the position switch 16 in its zero position the energizing circuit for the timing relay 10 is interrupted before the same can respond. On the other hand, assuming position switch 16 is in a position other than its zero position, the timing relay 10 responds since the trip coil 12^b can be energized only after the limit switch 17 has been moved to a position corresponding to that of the position switch. The controller will thus operate in a manner similar to that hereinbefore described in connection with the double bucket operation thereof to provide for dumping of a selected number of loads into the furnace at six different points.

In connection with the foregoing it should be noted that although the controller is designed to provide for dumping of a selected number of loads at six equally spaced points the same can be readily modified to effect dumping of a selected number of loads at a different number of points.

What I claim as new and desire to secure by Letters Patent is:

1. The combination of a movable distributing device to which loads of material are supplied at a given point, of means for operating said device for transfer of the material supplied thereto, said means being adapted to effect different ranges of operation of said device for transfer of the material to different points, of means associated with said former means to provide for successive operations of said device through each of said ranges, said latter means including a selector part adapted to be set in different positions for selection of the number of successive operations of said device through each of said ranges.

2. The combination with a rotatable hopper into which loads of material are discharged at a given point, of a motor for operating the same, control means for said motor including an element having different positions to provide for different degrees of operation of said hopper by said motor, means for operating said element in accordance with the number of loads of material discharged into said hopper, said latter means including a selector device adapted to be set in different positions to provide for selection of the number of loads of material required

to move said element into each of its different positions.

3. The combination with a rotatable hopper into which loads of material are dumped at a given point, of a motor for operating the same, means for starting said motor upon dumping of each load of material into said hopper and for stopping the same after different predetermined ranges of operation of said hopper, said means including a control switch operable in a step by step manner and having different positions to provide for different ranges of operation of said hopper, and means for operating said switch in accordance with the number of loads of material dumped into said hopper, said latter means including a device adapted to be set in different positions to provide for selection of the number of loads of material required to effect each step of operation of said switch.

4. The combination with a rotatable hopper into which loads of material are dumped at a given point, of a motor for operating the same, means for starting said motor upon dumping of each load of material into said hopper and for stopping the same after different predetermined ranges of operation of said hopper, said means including a control switch operable in a step by step manner and having different positions to provide for different ranges of operation of said hopper, a second control switch operable in a step by step manner upon dumping of successive loads of material into said hopper and adapted upon a plurality of successive operations to effect a step of operation of said former switch, and means associated with said latter switch to select the number of operations thereof required to effect each step of operation of said former switch.

5. The combination with a rotatable hopper into which loads of material are dumped at a given point, of a motor for operating the same, means for starting said motor upon dumping of each load into said hopper, said means including a switch operable in a step manner upon dumping of successive loads into said hopper and means associated with said former means for effecting stopping of said motor upon different predetermined ranges of operation of said hopper, said latter means including a control switch operable in a step by step manner and having different positions to provide for different ranges of operation of said motor, means associated with said former switch and adapted upon a plurality of successive operations thereof to effect a step of operation of said latter switch and means including a part adapted to be set in different positions for selection of the number of operations of said latter switch which are required to effect a single step of operation of said former switch.

6. The combination with a rotatable dis-

tributing device, of operating means therefor to effect successive operations thereof through each of a plurality of different ranges, said means including a plurality of devices operable in a step by step manner, one of said devices being dependent for operation upon dumping of successive loads of material into said hopper and the other requiring a plurality of steps of operation of the former for each step of operation thereof, and means for effecting selection of the number of operations of said former element which are required to effect each step of operation of said latter element.

7. The combination with a movable distributing device and a drive therefor, of means for controlling said drive to effect successive operations of said distributing device through each of a plurality of different ranges, said means including means for automatically changing the range of operation of said distributing device upon a selected number of successive operations thereof through any one of said ranges, and means for effecting selection of the number of successive operations of said distributing device through each of said ranges.

8. The combination with a movable distributing device and a drive therefor, of means for controlling said drive to effect successive operations of said distributing device through each of a plurality of different ranges, said means including a control device movable into different positions for selection of the range of operation of said distributing device, means for automatically changing the position of said control device upon a selected number of successive operations of said distributing device through each of said ranges, and means for effecting selection of the number of successive operations of said device through each of said ranges.

In witness whereof, I have hereunto subscribed my name.
